ELLIS S. ARCHER, OF NEW YORK, N. Y., ASSIGNOR TO ARCHER, PAN-COAST & CO., OF THE SAME PLACE.

Letters Patent No. 75,510, dated March 17, 1868.

IMPROVEMENT IN LANTERNS.

The Schedule referred to in these Letters Patent and making part of the same.

TO ALL WHOM IT MAY CONCERN:

Be it known that I, ELLIS S. ARCHER, of New York, in the county of New York, and State of New York, have invented a certain new and useful Improvement in Lanterns; and I do hereby declare that the following is a full, clear, and exact description thereof, reference being had to the accompanying drawings, and to the letters of reference marked thereon.

My invention consists of improvements in the construction of the top of the case of the lantern, the manner in which, or the device by which, said top of the case is secured to the side or edge pieces of the said case; to the construction and manner of attaching the spring which holds the case in position upon the lamp when the lantern is in use.

Description of the Drawings.

Figure 1 is an edge view of the lantern.

Figure 2 is a vertical longitudinal central section of the same.

Figure 3 represents the plate which forms the top of the lantern, after being cut out, and before it has been bent into the proper shape.

Figure 4 is an edge view of the plate which forms the top of the lantern, partly bent into the proper form, and showing in red lines one of the edge or side pieces to which the top piece is attached, to illustrate the manner in which said top is attached to said side or edge pieces to form the frame of the lantern.

General Description.

The handle or bail A of the lantern is formed of wire, bent into the proper form, and upon the ends of which are formed loops, by means of which said bail or handle A is hinged or pivoted to ears B, formed on the wire guards C. The guards C are formed of wire, and are soldered or otherwise attached to the lower part of the frame of the lantern, thence ascending to the top of said lantern, where they are bent over upon themselves, as represented in fig. 1, so as to form the ears B, to which the bail or handle A is hinged or pivoted; thence they pass through holes in the overlapping edges of the cap F, through the holes D in the top piece E, and are then bent over to prevent their being withdrawn from their proper position, as represented in figs. 1 and 2.

F is the cap which covers the hole G, through which the products of combustion and heated air escape. Said cap F is secured to the top of the lantern by the ends of the wires which form the guards C, and the ears B, passing through holes in the side edges of said cap, which overlap the sides of the top piece E. The top piece E is cut out of a single piece of metal into the form represented in fig. 4, the parts H passing through slits cut in the side pieces I of the frame, as represented in fig. 4, after which they are bent over, as represented in fig. 1, so as to securely hold the top parts of the lantern together.

The glass sides of the lantern are held in place at the top by bending over the parts of the top pieces E, as represented in the drawings, and at the bottom by small pieces of metal K, soldered or otherwise attached to the lower parts of the frame. The upper parts of the lantern are hinged to the upper edge of one of the ends of the square lamp L, which forms the bottom or lower part of the lantern.

M are side pieces, forming the lower part of the frame of the lantern, and overlapping the sides of the square lamp L; they are also corrugated, so as to allow the air to pass in freely to the flame, and at the same time to guard against the light being extinguished by any sudden blast of air.

N is a no-chimney burner, which fits into a socket or hole in the top of the lamp L, without any screw-thread, and is kept in position therein by the wire or rod which carries the spur-wheels for raising and lowering the wick, passing under a catch on the top of the lamp L, (not shown); thence the said rod passes out through the side of the lantern, where it is kept in place by a notch in the lower edge of the lower part of the frame, shutting down over said rod, so that the wick may be raised or lowered, as required, without opening the lantern.

The lantern is kept closed, when in use, by the action of the spring-catch O, which descends perpendicularly along one of the ends of the lamp L, is then bent or struck up, as represented in fig. 2, so as to pass

through a slit in the said end of the lamp, and be closely along the inside of said end, in which position it is securely soldered.

The catch or projection P, for holding the lantern closed, is formed by punching or striking up a piece of the upper part of the spring, as represented in figs. 1 and 2, so that the catch or spring may act automatically in taking hold of and securing the lantern when closed, and yet may be readily forced back, and the upper part of the lantern released, when it is necessary to open said lantern. By which construction I obtain all the advantages of a square or abrupt catch without having to bend the metal short, and thus weakening it and making it liable to break.

By constructing the upper parts of the lantern as described, the parts which are liable to become heated are held together securely without the use of solder, and a great saving of material is accomplished, since, the parts being cut out separately, the manufacturer is able to raise up the smaller pieces of metal, and thus utilize a larger proportion of the material.

Claims.

I claim—

1. The combination of the top piece or plate E, constructed and formed as described, with the frame and side plates of a lantern; substantially as and for the purpose set forth.
2. The passing the spring through the side of the lamp, and soldering it upon the inside of said side, substantially as described.
3. The forming the catch of the spring by punching and striking out a portion of the spring itself, substantially as and for the purpose set forth.
4. The combination of the spring O, constructed and attached as described, with the lamp and frame of a lantern, substantially as described and for the purpose set forth.

ELLIS S. ARCHER.
